(57) **CLAIM**

The ornamental design for a display screen with animated graphical user interface, as shown and described.

DESCRIPTION

FIG. 1 is a master front view of a display screen with animated graphical user interface of a first embodiment showing our new design;

FIG. 2 is a front view of a first varying state of the first embodiment thereof;

FIG. 3 is a front view of a second varying state of the first embodiment thereof; and,

FIG. 4 is a front view of a third varying state of the first embodiment thereof.

The solid line rectangle immediately surrounding the black rectangle shows the display screen and forms part of the claimed design. All broken lines outside the display screen show portions of a device. All broken lines inside the display screen show portions of the graphical user interface. None of the aforementioned broken lines form no part of the claimed design.
